UNITED STATES PATENT OFFICE.

ARTHUR H. KINDER, OF DORCHESTER, MASSACHUSETTS, ASSIGNOR TO L. C. CHASE & CO., OF BOSTON, MASSACHUSETTS, A FIRM.

HORSE-BLANKET.

1,175,272.

Specification of Letters Patent.

Patented Mar. 14, 1916.

Application filed November 2, 1911. Serial No. 658,122.

To all whom it may concern:

Be it known that I, ARTHUR H. KINDER, a citizen of the United States, and resident of Dorchester, county of Suffolk, State of Massachusetts, have invented an Improvement in Horse-Blankets, of which the following description, in connection with the accompanying drawing, is a specification, like characters on the drawing representing like parts.

This invention has for its object the production of a horse-blanket of novel construction whereby overlapping breast portions of large area are provided without waste of material, the construction of the breast portions being such that they are substantially self-supporting when in overlapped position.

Blankets have been made heretofore with elongated portions to overlap and more or less protect the breast of the animal, but not only has there been waste in cutting the blanket to provide such portions but in the finished blanket such breast portions have a tendency to drop or sag down. To overcome this tendency recourse has been had to fastening means which not only connect the breast flaps but serve to stiffen and hold the latter in position, such fastening means greatly increasing the cost of the blanket and also adding unduly to its weight. Again, the breast flaps have heretofore been of comparatively small area, diminishing the protection to the animal where it is most needed, and previous attempts to increase the protective area have resulted in a decrease in the neck opening for a given size of blanket, which is of itself objectionable, or in an increase in the waste of material in cutting.

In my present invention I have so shaped the forward edge of each blanket side that it presents a reverse contour line, preferably a curve, from the upper to the lower edge, the concave upper part of the contour line forming one side of the neck opening and the oppositely turned lower, or convex part of the contour line forming a part of the boundary of the breast portion or flap. By this construction the two sides or halves of the blanket present breast portions of large area, without any objectionable variations in the neck opening, and the shape of the breast flap causes it to be in a sense self supporting. That is, instead of a tendency

to drop or sag when the breast flaps are overlapped, they tend to maintain their proper position, and consequently simple fastening members of light weight and low cost can be used. So, too, in cutting the blanket in accordance with my invention I eliminate all waste, and in fact save from six to twelve inches of fabric in cutting, in the preferred form of my invention.

The various novel features of my invention will be fully described in the subjoined specification and particularly pointed out in the following claims.

Figure 1 is a front elevation of a horse-blanket embodying my present invention, the breast portions being overlapped in the position occupied when the blanket is in use; Fig. 2 is a detail in side elevation of the forward end of the blanket, the sides thereof being superposed and spread out flat; Fig. 3 is a diagrammatic view showing the blank and the manner of dividing it to provide two like but reversed halves or blanket-sides, without waste, in accordance with my invention; Fig. 4 is a detail showing a slightly modified form of contour or dividing line, whereby the two sides of the blanket are the same but reversed when cut from the blank.

In the old method of cutting blankets a strip of fabric equal in width to the depth of the desired blanket is divided by two equal and parallel cuts extended inward from and at right angles to opposite longitudinal edges of the blank, said cuts meeting two oppositely curved cuts, to form the two reversed halves. This method of cutting results in three pieces of waste, which waste is only increased by an attempt to increase the breast flaps, and in addition the neck opening of the completed blanket is varied improperly. Such elongation of the breast flaps will only increase the tendency thereof to drop or sag when the blanket is in use. Again, the total length of the blank must be greater than double the length of a predetermined blanket by an amount depending on the size of the waste pieces made between adjacent straight and curved cuts, thus taking up more fabric than can be used. As blankets are cut by superposing a large number of plies of fabric it will be obvious that the waste is a serious item.

Referring to Fig. 3, the elongated rectangular blank C is twice the total length of

the blanket to be cut, and the width of the blank is equal to the depth of the blanket. In the preferred form of my invention this blank is divided by a continuous symmetrical and reversely curved cut extending from one to the other longitudinal edge of the blank, the two lobes c, c' of the said cut being symmetrically disposed on opposite sides of a diagonal line d, d' , and of equal length 10 and curvature. The reverse curve c, c' crosses or intersects this line at the point c' midway between the ends thereof and also midway between the opposite ends of the blank C , and it will be seen that the point d 15 is at a distance from either end of the blank equal to the distance of the point d' from the other end of said blank. Consequently the blank is divided into two symmetrical but reversed halves C^x, D^x , without any 20 waste whatever, the portion c forming one side of the neck opening for the half C^x and bounding the forward edge of the breast portion or flap D^x of the half D^x , while the portion c' of the contour or dividing line 25 forms one side of the neck opening of the half D^x and bounds the forward edge of the breast portion C^x of the half C^x . If the fabric from which the halves are thus cut is alike on each face the halves C^x and D^x can 30 be at once superposed and connected by a usual back seam, and finished up in usual manner, forming no part of my invention. In practice, however, blanket fabric has a 35 right face and a wrong face, and it is usual to lay eight or ten, or more, plies of the fabric one upon another and cut out the pattern by a power cutter, each two adjacent plies of fabric being oppositely faced, and when that is done it will be manifest that 40 for every two such plies the division cut c, c' Fig. 3, will provide the sides for two blankets, without any waste.

The waste heretofore made has been a serious item, and when it is understood that 45 by my invention I save on each cutting a strip of fabric from six to twelve inches wide, depending upon the size of the blanket, it will be apparent that the saving in fabric alone by my invention is very large. 50 Viewing Fig. 1 it will be seen that the completed blanket comprises two like sides or halves E, F , each having its forward edge formed by a symmetrical reversed contour line, preferably a curve, incurved from its upper edge, as at e, f , to form the neck opening, and outcurved from the mid-point of the curve, as at e', f' , to the lower straight edges e^x, f^x , the out-curved portions bounding the forward edges of the extended breast 55 portions or flaps E^x, F^x of large area.

In Fig. 1 the outer breast flap F^x is broken out to show a part of the breast flap E^x beneath it.

The overlapped breast portions E^x, F^x 60 provide a double thickness or covering of a

large area over the breast of the horse at the point where such protection is most essential, and owing to the contour of the front edge of each blanket side the breast flaps instead of falling or sagging downward are 70 held substantially in a position shown in Fig. 1 with their lower straight edges e^x, f^x substantially in a straight line. In other words, the breast flaps are self-supporting and tend when overlapped to stay in proper 75 position instead of tending to sag downward.

By reason of the tendency of the breast flaps to remain in proper position, I am enabled to use very simple fastening members. 80 Herein I have shown a separable two-part fastening comprising a loop member g and a detachable snap hook member g' , and I find that a pair of such two-part fastenings is all sufficient, the loop members g being attached to one breast flap as F^x , Fig. 1, near its curved and forward edge, and the co-operating members g' are attached to the other flap E^x at the proper height from the lower edge of the blanket side, and at such 90 a distance from its curved edge e' that when the flaps are overlapped the fastening devices can be hooked together.

Fastening members of the general type shown are extremely cheap, they are very 95 light in weight, and by their means the breast flaps can be readily attached or detached as desired.

If a blanket is made in accordance with my present invention and the two sides are 100 laid out flat one upon the other, the forward reversely and symmetrically curved edges will superpose one upon the other as shown in Fig. 2.

The large area of the breast portions of 105 the blanket in accordance with my invention is secured without any improper decrease in the neck opening, for any given size blanket, and without any waste whatever in cutting the material as has been pointed out hereinbefore, and as the breast flaps are substantially self-sustaining the function of the fastening members is merely to hold them in overlapped position upon the horse, and not to sustain them vertically in proper position. 110

As has been stated I prefer to form the dividing line or cut as a continuous reverse and symmetrical curve, not only for convenience in cutting but also because the appearance of the finished blanket is attractive and neat, but it will be obvious that the dividing line need not necessarily be a continuous or curved line.

Referring to Fig. 4 the dividing line is 115 shown as composed of several straight portions h, h', h^2 , the portions h, h' being of equal length and extended in parallelism in opposite directions from the opposite ends of the diagonal line k, k' , while the middle or joining part h^2 intersects the diagonal

line at k^* , midway between its upper and lower ends.

The portion of the dividing line from the upper end to the center of the line k, k' is 5 symmetrical to but reversed with relation to the portion of the dividing line from the center of the line k, k' to its lower end, so that there is no waste in cutting, and the forward edge of each blanket side will present a symmetrical reverse contour line, for 10 the neck opening and breast flaps of the finished blanket.

Having fully described my invention, what I claim as new and desire to secure by 15 Letters Patent is:

1. A horse blanket having two sides of the same size and shape united at their upper edges by a back seam, the forward edge of each side presenting a continuous reversely 20 formed contour line extending from the upper to the lower edge of the side and symmetrical with respect to its central point, whereby there is provided a neck opening and two similar extended breast portions 25 which, when the blanket is in place, overlap and are sustained in proper position with their lower edges in substantial alinement by reason of the contour of the forward edges, and whereby, by reason of the symmetrical reversely formed contour of the 30 forward edges of the sides, the said edges,

when the sides are reversed, match, thus enabling the sides to be cut without waste of material, and means detachably to connect said breast portions. 35

2. A horse blanket having two sides of the same size and shape united at their upper edges by a back seam, the forward edge of each side presenting a continuous reversely curved contour line extending from the upper to the lower edge of the side and symmetrical with respect to its central point, whereby there is provided a neck opening and two similar extended breast portions which, when the blanket is in place, overlap 40 and are sustained in proper position with their lower edges in substantial alinement by reason of the contour of the forward edges, and whereby, by reason of the symmetrical reversely curved contour of the forward edges of the sides, the said edges, when the sides are reversed, match, thus enabling the sides to be cut without waste of material, and means detachably to connect said breast portions. 45 50 55

In testimony whereof I have signed my name to this specification, in the presence of two subscribing witnesses.

ARTHUR H. KINDER.
